UNITED STATES PATENT OFFICE.

HENRY PAAR, OF CANTON, OHIO, ASSIGNOR OF TWO-THIRDS TO JOHN L. ARNOLD AND ADAM THOMAS, OF SAME PLACE.

DESIGN FOR A HORSESHOE.

SPECIFICATION forming part of Design No. 29,938, dated January 3, 1899.

Application filed November 25, 1898. Serial No. 697,465. Term of patent 14 years.

To all whom it may concern:

Be it known that I, HENRY PAAR, a citizen of the United States, residing at Canton, in the county of Stark and State of Ohio, have invented and produced a new and original Design for Horseshoes, of which the following is a specification, reference being had to the accompanying drawings, forming a part thereof.

10 Figure 1 is a perspective view. Fig. 2 is a side elevation. Fig. 3 is a transverse section through line $x-x$, Fig. 1.

As shown in the drawings, the leading or material feature of my design consists of the 15 oval or egg-shaped flanges 1 located at the heel ends of the shoe proper and upon the bottom or under side thereof, the larger portion of said flanges being located at the extreme heel ends of the horseshoe and the 20 smaller portions being located toward the toe end of the shoe.

Upon the upper sides of the horseshoe-body 2 are located the flanges 3 and 4. The flanges

3 are located upon the inner and outer edges of the heel ends of the horseshoe-body 2 and 25 are narrowed as they approach the toe end of the horseshoe-body 2. The flanges 4 follow the curvature of the flanges 3 and also the curvature of the horseshoe-body 2.

The egg-shaped flanges 1 are formed tapering in cross-section, as illustrated in Fig. 3, the larger portions of said flanges being located upon the bottom or under side.

Having fully described my invention, what I claim as new, and desire to secure by Letters 35 Patent, is—

The design for a horseshoe, substantially as shown and described.

In testimony that I claim the above I have hereunto subscribed my name in the presence 40 of two witnesses.

HENRY PAAR.

Witnesses:

J. A. JEFFERS,
F. W. BOND.
